NUT FOR STRINGED MUSICAL INSTRUMENTS

Richard Furgiuele, Mentic, Pa.

Application December 29, 1939, Serial No. 311,685

1 Claim. (Cl. 84—314)

The present invention relates to new and useful improvements in nuts for stringed musical instruments, particularly Hawaiian guitars and has for its primary object to provide, in a manner as 5 hereinafter set forth, a device of this character which is adapted to level the upper surfaces of all of the strings regardless of different sizes and arrangements thereof for assuring uniform contact by the steel, thus greatly improving the 10 tone of the instrument in addition to facilitating the playing thereof.

Another very important object of the invention is to provide a nut of the aforementioned character which may be expeditiously mounted for 15 use on a conventional instrument without the necessity of making structural alterations therein.

Other objects of the invention are to provide a nut for Hawaiian guitars and other stringed 20 musical instruments which will be comparatively simple in construction, strong, durable, compact, attractive in appearance and which may be manufactured at low cost.

All of the foregoing and still further objects 25 and advantages of the invention will become apparent from a study of the following specification, taken in connection with the accompanying drawing wherein like characters of reference designate corresponding parts throughout the 30 several views, and wherein:

Figure 1 is a top plan view of a portion of a 35 stringed instrument equipped with a nut constructed in accordance with the present invention.

Figure 2 is a cross sectional view through the device, taken substantially on the line 2—2 of 40 Figure 1.

Figure 3 is a fragmentary view in vertical section, taken substantially on the line 3—3 of 45 Figure 1.

Referring now to the drawing in detail, it will be seen that the reference numeral 1 designates the outer portion of the neck of a conventional Hawaiian guitar which is provided with the usual 45 frets 2. At its outer end, the neck 1 terminates in a head 3 provided with winding keys, etc., 4 for adjusting the tension of the strings 5.

The embodiment of the present invention which has been illustrated comprises what may 50 be considered a base bar 6 of suitable metal which is adapted to be mounted on the usual nut 7 of the instrument. Retaining fingers 8 depend from one side of the bar 6 for engagement with the corresponding side of the usual instrument 55 nut 7. The bar 6 is triangular in cross section.

Rigidly mounted on the bar 6 is a pair of spaced, parallel upper bars 9 which are also of substantially triangular cross section. Integral webs 10 rigidly connect the bars 6 and 9. It will be observed that the apices of the upper bars 9 5 are disposed lowermost for engagement with the strings 5 of the instrument. It will also be noted that the apex of the bar 6 is located intermediate the vertical planes of the bars 9 and has formed therein, intermediate the webs 10, spaced 10 notches 11 for the reception of the strings 5. The apices of the bars 6 and 9 are in substantially the same horizontal plane and are somewhat rounded to avoid cutting the strings 5. This is illustrated to advantage in Fig. 2 of the 15 drawing.

It is thought that the manner in which the device functions will be readily apparent from a consideration of the foregoing. Briefly, the device is mounted on the usual nut 7 of the instrument and the strings 5 are inserted therethrough and tightened in the usual manner. As the left hand bar 9, as viewed in Figure 2 of the drawing, presses downwardly on the strings 5 the upper surfaces of said strings will be leveled 20 regardless of the size or arrangement of said strings thereby assuring uniform contact with the steel when the instrument is being played. The three point contact provided by the bars 6 and 9 causes the device to be held firmly in position on the nut 7 by the strings 5. If desired, the device may be mounted for use on the fret board of the instrument on one of the frets 2. That is, the retaining fingers 8 may be engaged with one of the frets 2. Also, the use of the 25 device as a permanent nut on an Hawaiian guitar, rather than as an auxiliary nut, is contemplated.

It is believed that the many advantages of a nut for stringed musical instruments constructed in accordance with the present invention will be 30 readily understood and although a preferred embodiment of the device is as illustrated and described, it is to be understood that changes in the details of construction may be resorted to which will fall within the scope of the invention 35 as claimed. For example, the device may be mounted adjacent the usual bridge (not shown) of the instrument for leveling the strings 5 at this end of said instrument. To facilitate use of the device in this manner the retaining fingers 50 8 may be eliminated. Also, while the element 6 as illustrated is substantially triangular in cross section, said element 6 may be of any other suitable cross sectional shape, such as circular, semi-circular, etc.

What is claimed is:

A nut for musical instruments of the type including a neck and a plurality of strings over said neck, comprising a bar of substantially triangular cross section adapted to be mounted on the instrument beneath the strings, the apex of said bar having a plurality of notches therein for the reception of the strings, a pair of spaced, parallel bars of substantially triangular cross section engageable with the upper surfaces

of the strings on opposite sides of the first named bar for leveling said upper surfaces, integral webs rigidly connecting the first and second named bars, the apices of the second named bars being disposed lowermost for contact with the strings and substantially in the horizontal plane of the apex of the first named bar, and means for securing said first named bar to the instrument.

RICHARD FURGUELE. 10
